COMBINED BATHTUB SPOUT AND HAND GRIP

Jack L. Bilkiss, 913 N. Los Angeles St.,
Santa Monica, Calif.

Filed Sept. 21, 1964, Ser. No. 81,802

Term of patent 14 years

(Cl. D91—3)

FIG. 1 is a perspective view of a combined bathtub spout and hand grip embodying my new design;

FIG. 2 is a side view of my new design showing the side thereof opposite that visible in FIG. 1; and

FIG. 3 is a bottom view thereof.

The dominant features of my design reside in the portions shown in full lines.

I claim:

The ornamental design for a combined bathtub spout and hand grip, substantially as shown and described.
